UNITED STATES PATENT OFFICE

132,458

DESIGN FOR A COSMETIC CASE

Jean Otis Reinecke, Oak Park, Ill., assignor to Louis S. Reller, Chicago, Ill.

Application November 21, 1941, Serial No. 104,236

Term of patent 14 years

To all whom it may concern:

Be it known that I, Jean Otis Reinecke, a citizen of the United States, residing at Oak Park, in the county of Cook and State of Illinois, have invented a new, original, and ornamental Design for a Cosmetics Case, of which the following is a specification, reference being had to the accompanying drawings, forming part thereof, in which

Fig. 1 is a front elevational view of a cosmetics case embodying my new design;

Fig. 2 is an end elevational view thereof as seen from the left in Fig. 1;

Fig. 3 is a rear elevational view thereof;

Fig. 4 is a top plan view thereof;
Fig. 5 is a bottom plan view thereof;
Fig. 6 is a view similar to Fig. 2 but in open position; and

Fig. 7 is a perspective view thereof in open position.

The characteristic features of the design for the cosmetics case disclosed reside in the internal portions thereof having the configuration shown.

I claim:

The ornamental design for a cosmetics case, as shown and described.

JEAN OTIS REINECKE.
